UNITED STATES PATENT OFFICE.

JAMES E. LOSHBOUGH, OF ELKHART, INDIANA, ASSIGNOR, BY MESNE ASSIGNMENTS, TO STURGIS STEEL GO-CART COMPANY, OF STURGIS, MICHIGAN.

FOLDING BABY-CARRIAGE.

No. 882,902.

Specification of Letters Patent. Patented March 24, 1908.

Application filed June 14, 1907. Serial No. 379,079.

To all whom it may concern:

Be it known that I, JAMES E. LOSHBOUGH, a citizen of the United States, residing at the city and county of Elkhart, State of Indiana, 5 have invented certain new and useful Improvements in Folding Baby-Carriages, of which the following is a specification.

This invention relates to improvements in children's carriages.

10 It relates particularly to improvements in folding carriages, such as are commonly designated as go-carts, although certain features thereof are adapted for use in other relations.

The main objects of this invention are, 15 first, to provide in a child's carriage of the class described an improved spring axle support. Second, to provide an improved adjustable foot rest. Third, to provide in a structure of the class described an improved 20 means for locking or holding it in its folded or collapsed position.

Further objects, and objects relating to details of construction, will definitely appear from the detailed description to follow.

25 I accomplish the objects of my invention by the devices and means described in the following specification.

The invention is clearly defined and pointed out in the claims.

30 A structure embodying the features of my invention is clearly illustrated in the accompanying drawing, forming a part of this specification, in which,

Figure 1 is a side elevation of a structure 35 embodying the features of my invention, the foot rest being shown by dotted lines in its elevated position. Fig. 2 is an enlarged section taken on a line corresponding to line 2—2 of Fig. 1, showing structural details of the 40 spring axle support. Fig. 3 is a detail side elevation of the structure in its collapsed position. Fig. 4 is an enlarged detail front elevation, showing the foot rest supports and adjusting means therefor. Fig. 5 is an enlarged detail taken on a line corresponding 45 to line 5—5 of Fig. 4. Fig. 6 is an enlarged longitudinal detail section taken on a line corresponding to line 6—6 of Fig. 5. Fig. 7 is an enlarged detail section taken on a line 50 corresponding to line 7—7 of Fig. 4, showing details of the latch mechanism. Fig. 8 is a detail view, showing a modification of the latch mechanism. Fig. 9 is a vertical section taken on a line corresponding to line 9—9 of 55 Fig. 8.

In the drawing, the sectional views are taken looking in the direction of the little arrows at the ends of the section lines, and similar numerals of reference refer to similar parts throughout the several views. 60

Referring to the drawing, the side pieces 1 of the frame are relatively fixed or rigid and are provided with a handle at their upper ends. These side pieces are preferably curved downwardly and forwardly at their lower ends. On the lower end of the side pieces 1 is the axle for the forward wheels. The side pieces 2 by which the rear axle is carried are connected to the side pieces 1 by the pivots 3. The side pieces 2 are made up 70 of sections 4 and 6. The meeting ends of the sections 4 and 6 are overlapped and secured together by a pivot 8. The ends of the sections 4 and 6 are provided with laterally projecting arms 5 and 7, respectively, 75 the pivot 8 being located between the arms.

The spring 9 is connected to the arms 5 and 7, so that on movement of the sections on their connecting pivot, stress is put on the spring, thereby providing a spring support for the rear axle. The side rails 10 are provided with longitudinal slots in which the hooks 12 on the upper ends of the side pieces 2 are engaged. The side rails 10 are pivoted to the fixed side pieces 1 at 13, so as to 85 swing upwardly in folding the carriage, as clearly appears in Fig. 3.

The links 15 are pivotally connected to the side rails at their forward ends, the same being mounted on the pivots 23. The upper 90 ends of these links are connected by the side bars 16 to the side pieces 1, the bars being secured to the side pieces by means of the pivots 17 and to the links 15 by the pivots 18.

The seat 19 is carried by the side rails and 95 the back 20 is preferably mounted on the pivot 13, but, as the details of its connections and adjustment of the back form no part of this invention, they are not here illustrated.

The foot rest 33 is carried by a pair of arms 21. These arms are preferably connected at their upper ends by a cross piece 22. The foot rest carrying arms 21 are pivotally mounted on the pivots 23 to swing 105 thereon. The foot rest is adjustably supported by means of a latch preferably consisting of the latch rods 24, which are arranged through the arms and adapted to engage suitable perforations as 14 provided 110

therefor in the forward ends of the side rails. These latch rods also serve to hold the carriage in its collapsed or folded position, as they are adapted to engage in the slots 11 in the side rails when the carriage is folded; see Fig. 3. The latch is thus adapted to hold the foot rest in its adjusted position, and also to serve as a lock for holding the carriage in its collapsed or folded position.

10 The inner ends of the latch rods are provided with finger pieces 25 adapted to be grasped by the operator with the thumb and finger, so that they are both disengaged at the same time. The inner ends of the 15 rods are supported by hangers 26 carried by the cross piece 22 for the foot rest carrying arms 21. A stop, as 25', is provided to limit the inward movement of the latch rods. The latch rods are held normally outward by 20 means of the springs 27, the inner ends of which bear against the hangers 26 and the outer ends against collars 28, which are pinned to the latch rods.

In Figs. 8 and 9, I show a modified construction in which an A-shaped spring is arranged between the hanger arms, it being secured at its upper end by means of the clip 30, its arms engaging the finger pieces of the latch rods. This modified structure has the 25 advantage of simplicity in manufacture. The foot rest 33 is pivoted to the lower ends of the carrying arms therefor, so that it may be folded up when the structure is collapsed. To secure this collapsing automatically, I provide the foot rest with a rearwardly projecting lug 31, adapted to engage a lug 32 on one of the side rails when the structure is folded, which automatically swings it on its pivot. By connecting the side pieces 2 of the frame 35 as I have described, I secure a very desirable spring and at the same time one which is economical and durable.

It is the common practice to form the side pieces 2 of spring material. These springs 45 are, however, expensive to produce, and in practice it is very difficult to form and arrange them so that the springs on both sides of the wheel will track.

My improved adjustable foot rest is very 50 simple in construction and quickly and easily adjusted. The structure folds compactly and, when folded, is effectively held in its folded position.

I have illustrated and described my improvements in detail in the form preferred 55 by me on account of structural simplicity and economy. I am, however, aware that they are capable of considerable variations in structural details without departing from 60 my invention, and I desire to be understood as claiming the same specifically as illustrated as well as broadly.

Having thus described my invention, what 65 I claim as new and desire to secure by Letters Patent is:

1. In a carriage, the combination with an axle, of a support therefor, comprising two sections arranged with their ends overlapped, said sections having laterally-projecting arms on their overlapped ends, a pivot for 70 said sections arranged between the said arms thereof, and a coiled spring connected to the said arms, for the purpose specified.

2. In a carriage, the combination with an axle, of a support therefor, comprising a pair 75 of pivotally connected sections having laterally-projecting arms thereon, and a coiled spring connected to said arms, for the purpose specified.

3. In a carriage, the combination with an 80 axle, of a support therefor, comprising a pair of pivotally connected sections having laterally-projecting arms thereon, and a spring connection for said arms, for the purpose specified.

4. In a carriage, the combination with a body, of an axle; a support therefor comprising a pair of pivotally connected members, one of said members being connected to said body and the other to said axle; 90 and a spring arranged to connect said members so that it is put under stress by the movement of the members on their connecting pivot, for the purpose specified.

5. In a folding carriage, the combination 95 of the downwardly and forwardly projecting fixed side pieces, having a handle at their upper ends; adjustable side pieces arranged across and pivoted to said fixed side pieces; axles carried by said side pieces; side rails 100 to which the upper ends of said adjustable side pieces are slidably connected pivotally mounted on said fixed side pieces; vertically arranged links pivoted at the forward ends of said side rails; side bars pivoted to the 105 upper ends of said vertically arranged links and said fixed side pieces; a foot rest; supporting arms therefor pivotally secured to the forward ends of said side rails; a pair of latch rods having finger pieces at their inner 110 ends slidably arranged through the supporting arms of said foot rest; hangers for the inner ends of said latch rods through which they are slidably arranged, said side rails being provided with a plurality of holes 115 adapted to receive said latch rods for adjustably supporting said foot rest, said latch rods being adapted to automatically engage said side rails for holding the carriage in its collapsed or folded position; coiled springs arranged on said latch rods with their inner ends bearing against the hangers therefor; and collars secured to said latch rods adapted to receive the thrust of said springs whereby said latch rods are held normally outward.

6. In a folding carriage, the combination of the downwardly and forwardly projecting fixed side pieces, having a handle at their upper ends; adjustable side pieces arranged across and pivoted to said fixed side pieces; 120

axles carried by said side pieces; side rails to which the upper ends of said adjustable side pieces are slidably mounted on said fixed side pieces; vertically arranged links

5 pivoted at the forward ends of said side rails; side bars pivoted to the upper ends of said vertically arranged links and said fixed side pieces; a foot rest; supporting arms therefor pivotally secured to the forward
10 ends of said side rails; a pair of latch rods having finger pieces at their inner ends slidably arranged through the supporting arms of said foot rest; hangers for the inner ends of said latch rods through which they are slidably arranged, said side rails being provided with a plurality of holes adapted to receive said latch rods for adjustably supporting said foot rest, said latch rods being adapted to automatically engage said side rails for holding
15 the carriage in its collapsed or folded position; and springs arranged to hold said latch rods normally outward.

7. In a folding carriage, the combination of the downwardly and forwardly projecting fixed side pieces, having a handle at their upper ends; adjustable side pieces arranged across and pivoted to said fixed side pieces; axles carried by said side pieces; side rails to which the upper ends of said adjustable side pieces are slidably connected pivotally mounted on said fixed side pieces; vertically arranged lin's pivoted at the forward ends of said side rails; side bars pivoted to the upper ends of said vertically arranged lin's and said fixed side pieces; a foot rest; supporting arms therefor pivotally secured to the forward ends of said side rails; a pair of latch rods having finger pieces at their inner ends slidably arranged through the supporting arms of said foot rest, said side rails being provided with a plurality of holes adapted to receive said latch rods for adjustably supporting said foot rest; coiled springs arranged on said latch rods with their inner ends bearing against the hangers therefor; and collars secured to said latch rods adapted to receive the thrust of said springs whereby said latch rods are held normally outward.

8. In a folding carriage, the combination
50 of the downwardly and forwardly projecting
fixed side pieces, having a handle at their
upper ends; adjustable side pieces arranged
across and pivoted to said fixed side pieces;
axles carried by said side pieces; side rails
55 to which the upper ends of said adjustable
side pieces are slidably connected pivotally
mounted on said fixed side pieces; vertically
arranged links pivoted at the forward ends of
said side rails; side bars pivoted to the upper
60 ends of said vertically arranged links and
said fixed side pieces; a foot rest; support-
ing arms therefor pivotally secured to the
forward ends of said side rails; and a pair of
latch rods having finger pieces at their inner
65 ends slidably arranged through the support-

ing arms of said foot rest, said side rails being provided with a plurality of holes adapted to receive said latch rods for adjustably supporting said foot rest.

9. In a folding carriage, the combination of the downwardly and forwardly projecting fixed side pieces, having a handle at their upper ends; adjustable side pieces arranged across and pivoted to said fixed side pieces; axles carried by said side pieces; side rails slotted to receive the upper ends of said adjustable side pieces pivotally mounted on said fixed side pieces; vertically arranged links pivoted at the forward ends of said side rails; side bars pivoted to the upper ends of said vertically arranged links and said fixed side pieces; a foot rest; supporting arms therefor pivotally secured to the forward ends of said side rails; and a latch adapted to hold said foot rest adjustably in position and to lock the said carriage in its collapsed or folded position. 70
75
80
85

10. In a folding carriage, the combination with the pivoted side rails; a seat carried thereby; a foot rest; supporting arms therefor pivotally secured to the forward ends of said side rails; a pair of latch rods having finger pieces at their inner ends slidably arranged through the supporting arms of said foot rest; hangers for the inner ends of said latch rods through which they are slidably arranged; coiled springs arranged on said latch rods with their inner ends bearing against the hangers therefor; and collars secured to said latch rods adapted to receive the thrust of said springs whereby said latch rods are held normally outward, said side rails being provided with a plurality of holes adapted to receive said latch rods for adjustably supporting said foot rest, said latch rods being adapted to automatically engage said side rails for holding the carriage in a collapsed or folded position. 90 95 100 105

11. In a folding carriage, the combination with the pivoted side rails; a seat carried thereby; a foot rest; supporting arms therefor pivotally secured to the forward ends of said side rails; a pair of latch rods having finger pieces at their inner ends slidably arranged through the supporting arms of said foot rest; hangers for the inner ends of said latch rods through which they are slidably arranged; and springs arranged to hold said latch rods normally outward, said side rails being provided with a plurality of holes adapted to receive said latch rods for adjustably supporting said foot rest, said latch rods being adapted to automatically engage said side rails for holding the carriage in a collapsed or folded position. 110 115 120 125

12. In a folding carriage, the combination with the pivoted side rails, of a seat carried thereby; a foot rest; supporting arms therefor pivotally secured to the forward ends of said side rails; a pair of latch rods 130

having finger pieces at their inner ends slidably arranged through the supporting arms of said foot rest; hangers for the inner ends of said latch rods through which they are 5 slidably arranged; coiled springs arranged on said latch rods with their inner ends bearing against the hangers therefor; and collars secured to said latch rods adapted to receive the thrust of said springs whereby 10 said latch rods are held normally outward, said side rails being provided with a plurality of holes adapted to receive said latch rods for adjustably supporting said foot rest.

13. In a folding carriage, the combination 15 with the pivoted side rails, of a seat carried thereby; a foot rest; supporting arms therefor pivotally secured to the forward ends of said side rails; a pair of latch rods having finger pieces at their inner ends slidably arranged through the supporting arms 20 of said foot rest; hangers for the inner ends

of said latch rods through which they are slidably arranged; and springs arranged to hold said latch rods normally outward, said side rails being provided with a plurality of 25 holes adapted to receive said latch rods for adjustably supporting said foot rest.

14. In a folding carriage, the combination with the pivoted side rails; a foot rest; supporting arms therefor pivotally secured to the forward ends of said side rails; and a latch adapted to hold said foot rest adjustably in position and to hold the carriage in its folded or collapsed position.

In witness whereof, I have hereunto set 35 my hand and seal in the presence of two witnesses.

JAMES E. LOSHBOOUGH. [L. s.]
